UNITED STATES PATENT OFFICE

100,101

DESIGN FOR A TEXTILE FABRIC

Lawrence N. Hale, Leaksville, N. C., assignor to
Marshall Field & Company, Chicago, Ill., a
corporation of Illinois

Application February 26, 1935, Serial No. 55,628

Term of patent 7 years

To all whom it may concern:

Be it known that I, Lawrence N. Hale, a citizen of the United States, residing at Leaksville, in the county of Rockingham, State of North Carolina, have invented a new, original, and ornamental Design for a Textile Fabric, of which the following is a specification, reference being had to the accompanying drawing, forming part thereof.

The fabric forming the subject matter of this

application is a thick, heavy woolen textile, used for children's snow suits.

The figure is a plan view of a textile fabric showing my new design.

I claim:

The ornamental design for a textile fabric as shown and described.

LAWRENCE N. HALE.
